UNITED STATES PATENT OFFICE.

JOHN H. MONTSTREAM, OF HARTFORD, CONNECTICUT.

BED-SPRING-REINFORCING MEMBER.

1,240,755.

Specification of Letters Patent. Patented Sept. 18, 1917.

Application filed December 20, 1915. Serial No. 67,721.

To all whom it may concern:

Be it known that I, JOHN H. MONTSTREAM, a citizen of the United States, residing at Hartford, in the county of Hartford and 5 State of Connecticut, have invented certain new and useful Improvements in Bed-Spring-Reinforcing Members, of which the following is a specification.

This invention relates to bed-spring reinforcing-members, the object of the invention 10 being to provide a simple article of this character by which transverse sagging of a bed-spring is effectually prevented, without affecting the proper longitudinal resiliency 15 of the spring and without interfering with the comfort of the occupant of the bed.

In the drawings accompanying and forming part of the present specification I have 20 illustrated in detail one form of embodiment of the invention which I will fully set forth in the following description. I do not restrict myself to this showing; I may depart therefrom in several respects within the 25 scope of the invention defined by the claims following said description.

Referring to said drawings:

Figure 1 is a perspective view of a bed-spring furnished with a reinforcing-member comprising the invention.

30 Fig. 2 is a top plan view of said reinforcing member.

Fig. 3 is a sectional detail showing one of the hooks in its two positions by full and dotted lines respectively, a portion of the 35 spring also appearing.

Fig. 4 is a detail view in perspective of one corner of the member, and

Fig. 5 is a transverse sectional view of the device.

40 Like characters refer to like parts throughout the several views, which are on different scales.

The bed-spring reinforcing-member is 45 preferably placed on top of the spring, and while advantageously it is removable, it need not always be so in all cases. As represented it has means by which it can be detachably connected with the spring, so that it may when desired be taken from operative 50 relation. While upon the spring said member supports the mattress, extending crosswise of the spring for practically the complete width thereof. It does not extend, however, the complete length of the spring 55 but is disposed nearly midway thereof, being a trifle nearer the head than the foot

of the spring in which position it is adapted best to resist the weights or stresses applied to the spring. The member possesses a certain amount of stiffness or rigidity 60 transversely of the bed-spring, not an abnormal amount for the device has a certain degree of resiliency laterally or transversely of the bed, enough preferably to insure it being comfortable yet still sufficient to prevent transverse dents or hollows being made in the spring. Said member is flexible longitudinally of the spring, and this flexibility is comparatively and in fact quite free to permit easy and natural longitudinal bending 65 of the spring. As I have noted I do not restrict myself to any particular construction by which I can secure the prime advantages set forth. In the drawings I have shown an organization which is highly 70 advantageous and which involves the invention. This I will describe in detail to comply with the statute and enable those skilled in the art to practice the invention.

In Fig. 1 the numeral 2 denotes a bed bottom equipped with the spring 3, the latter being partly illustrated in Fig. 3. The reinforcing-member is denoted in a general way by 4 and it has bars 5 of which there may be any desired number, the length of 85 each preferably virtually agreeing with the width of the spring 3. These crossbars are somewhat longitudinally resilient and are spaced apart which permits flexibility and ventilation; they may be made of any suitable material. Wood answers satisfactorily in this connection or sheet metal might be provided. While said cross bars individually possess a certain amount of longitudinal resiliency, they in the aggregate or collectively resist stresses applied to the spring. 90

In the present case this relative rigidity or stiffness of the reinforcing member longitudinally thereof or transversely of the bed spring, is secured by the comparatively close 100 arrangement of the bars or strips 5. Said cross bars are flexibly connected together for instance by the rods 6 of which there may as shown be two, the bars being perforated near their opposite ends for the 105 comparatively free passage of the rods 6. The terminals of the rod 6 are threaded to receive the nuts 7, constituting suitable end stops, washers as 8 being interposed between the nuts 7 and the adjacent cross bars 5. 110 The nuts present a convenient means for holding the parts of the reinforcing mem-

ber in assembled relation. Between the two central bars 5 I may as represented, dispose coiled springs 9 which encircle the rods 6 between said central cross bars, the springs bearing at their ends against said central cross bars or against washers as 10. Surrounding the rods 6 between the other cross-bars are spacing members or tubes as 11 bearing at their ends against washers as 12 fitted against adjacent faces of the cross bars. These spacing members 11 as will be clear separate the cross bars other than the two central ones, the necessary distance, while the springs 9 acting against opposite faces of the central cross bars force the two groups of cross bars outwardly firmly and substantially against the holding nuts 7. The rods 6 may be of wire of a size sufficient to insure proper bending between the cross bars, for example wire of approximately one-eighth inch in diameter answers my purpose.

While the reinforcing member might as may be inferred constitute a permanent part of the bed-spring, I prefer as already observed that it be in the form of an attachable element, and it will be equipped therefore with some suitable means for operatively connecting it with a spring. As shown each of the rods 6 has connected therewith latch members as 13 practically of Y or forked form perforated at their butts to freely receive the rods mentioned. From this it will be clear that the latches can be swung up or down. In Fig. 3 I have shown one of the latches 13 in its two positions by full and dotted lines respectively. When the latch is in the full line position and with the reinforcing member resting on the spring 3, the lower arm of the latch can be hooked into the spring. Should the reinforcing member be inverted what is shown as the upper arm of the latch can be engaged between the coils of the spring as shown by dotted lines in said Fig. 3. The bar 5 adjacent each latch may if desired be equipped with stops 14 in the form of pins to limit the motion of the latches.

As will be understood, the reinforcing member is susceptible of advantageous association with either new or old bed springs. When mounted upon a new spring it materially prolongs the life thereof by distrib-

uting the weight of the occupant or occupants of the bed uniformly across the whole width of the springs, the consequence being that each coil and strand supports its proper extent of the load. When mounted upon an old spring it has the effect of restoring and preserving the same.

What I claim is:

1. A bed-spring reinforcing-member relatively rigid in a direction transversely of the spring and flexible longitudinally of the spring and provided with hook means to engage into the fabric of the spring to hold the member against movement bodily with respect to the spring.

2. A bed-spring reinforcing-member comprising a plurality of cross bars, flexible elements extending freely through the cross bars near the ends thereof, stops on the ends of the flexible elements, springs carried by the flexible elements and acting against intermediate cross bars and tending to constantly force said intermediate cross bars outwardly, and spacing members carried by the flexible elements between the other cross bars to positively separate said other cross bars from each other.

3. A bed-spring reinforcing-member comprising cross bars, wires extending through the cross bars, nuts threaded on the ends of the wires and bearing against the outer sides of the end cross bars, springs coiled about the wires and bearing at their ends against the intermediate cross bars, the wires being provided with sleeves between the other cross bars to space said other cross bars from each other.

4. A bed-spring reinforcing-member comprising cross bars, wires extending through the cross bars, nuts threaded on the ends of the wires and bearing against the outer sides of the end cross bars, springs coiled about the wires and bearing at their ends against the intermediate cross bars, the wires being provided with sleeves between the other cross bars to space the said other cross bars from each other, and being also provided with latches to engage the bed-spring.

In testimony whereof I affix my signature in presence of two witnesses.

JOHN H. MONTSTREAM.
